UNITED STATES PATENT OFFICE.

JOHN Z. MILLER, OF HAGERSTOWN, MARYLAND, ASSIGNOR OF ONE-HALF TO GLENN G. GOLLING, OF HAGERSTOWN, MARYLAND.

FURNACE.

1,223,715.

Specification of Letters Patent. Patented Apr. 24, 1917.

Application filed March 20, 1916. Serial No. 85,437.

To all whom it may concern:

Be it known that I, JOHN Z. MILLER, a citizen of the United States, residing at Hagerstown, in the county of Washington 5 and State of Maryland, have invented a new and useful Furnace, of which the following is a specification.

The present invention appertains to furnaces, and aims to provide a novel and improved "one register" or "pipeless" hot air furnace for use in dwellings, churches, 10 school houses, and the like.

It is the object of the invention to provide a one register hot air heating furnace provided with novel means for the circulation of the cold and heated air, to enhance the efficiency of the furnace.

It is also within the scope of the invention to provide a hot air furnace of the nature indicated, which is of extremely simple construction, which can be readily manufactured and set up, and which will be satisfactory and efficient in use.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawings, wherein:—

Figure 1 is a plan view of the furnace.

Fig. 2 is a vertical section taken on the line 2—2 of Fig. 1, portions being shown in elevation.

Fig. 3 is a horizontal section taken on the line 3—3 of Fig. 2.

Fig. 4 is an elevation of the furnace, portions being broken away and shown in section.

Fig. 5 is a plan view of the furnace, showing the fire pot 1 and radiator 2 and accompanying parts, providing a heating plant which is inclosed by a sheet metal jacket or casing 3 provided at its lower end with diametrically offset 50 rectangular air inlet openings 4.

A square sheet metal box 5 is mounted upon the upper end of the jacket 3, and two opposite sides thereof are provided with rectangular openings 6 extending to the jacket and located above the openings 4.

Sheet metal channels 7 have their flanges or edges secured in any suitable manner to the walls of the jacket 3 so that their lower ends communicate with the openings 4, and the upper ends of said channels communicate with the openings 6. The upper ends of the channels 7 are inclined, as at 8, to extend to the side walls of the box 5 having the openings 6. The channels 7 are upon opposite sides of the jacket 3, and conduct the cold air downwardly along the opposite sides of the jacket to the lower end of the jacket. The upper end of the channel 7 being united with the box 5 provides an arch-like structure straddling the jacket 3 with the lower edge of the box 5 seated upon the upper end of the jacket and with the inwardly projecting flanges of the channels resting against and secured to opposite sides of the jacket. This provides for the effective application of the present improvement to the furnace proper, and it will be noted that fresh air in passing down the channels will come in contact with the jacket 3 to be heated thereby even before entering the jacket 80 through the openings 4.

A plurality, in this case five, short vertical pipes 9 are disposed within the box 5 in the arrangement illustrated in Figs. 1 and 3, and the lower ends of said pipes are attached to the upper end of the jacket 3 for conducting the heated air upwardly. The pipes 9 are spaced apart to provide cold air passages within the box 5.

The register, only one being used, embodies a floor plate 10 fitted in the floor 11 of the building, and having a plurality of depending annular flanges 12, one for each pipe 9, to fit the upper ends of said pipes. The plate 10 is preferably divided, as at 13, 95 to provide two sections, to facilitate the manufacture thereof. The floor plate 10 fits within the upper end of the box 5.

The present invention eliminates the use of pipes running from the furnace to various registers, and provides a furnace of extremely simple and inexpensive construction, which at the same time has an excellent heating efficiency. The cold air is drawn from the room or chamber which is heated, the same passing downwardly through the register into the register box 5 between the pipes 9, and the cold air passes from said box downwardly through the cold air channels 7 and thence through the openings of

into the lower portion of the jacket 3. It will be noted that the cold air in passing around the pipes 9 and along the jacket 3 will receive its initial heat, and after the air 5 is finally heated within the jacket 3 it passes upwardly through the pipes 9 into the room in a plurality of streams or currents. The hot air thus rises through the pipes 9 while the cold air passes downwardly around said 10 pipes. By providing the plurality of pipes 9, the circulation of air is increased, and the radiating surface between the pipes 9 and cold air within the box 5 is also increased. The register can be used below one 15 or more partitions, whereby the several pipes 9 supply the heated air into a plurality of rooms, the cold air being drawn off simultaneously through the single register.

As a means for humidifying the air, for 20 the comfort of the occupants, and to avoid the cracking of furniture, and the like, the back of one channel 7 is provided with a horizontal slot 14, and an inclined plate 15 has its upper edge portion secured to the 25 channel 7 by means of an angle member 16, said plate 15 projecting within the channel and sloping from said slot 14. A water receptacle or reservoir 17 is supported upon the outer side of said channel by means of 30 brackets 18 attached thereto, and an arched frame 19 is attached to the ends of said receptacle adjacent the channel 7. A horizontal shaft 20 is journaled through the limbs of the frame 19 and has secured thereon between its ends a copper roller 21 and a second horizontal shaft 22 above the shaft 20 extends through vertical slots 23 provided in the limbs of the frame 19, and a zinc roller 24 is mounted upon the shaft 22 between its ends and above the copper roller 21. One end of the shaft 22 is provided with a 35 crank 25 for rotating the roller 24. The shaft 22 is engaged through the downturned ends of a yoke 26 slidable vertically within 40 the frame 19, and an adjusting screw 27 is threaded through the central portion of the frame 19 and bears downwardly upon the yoke 26. The screw 27 enables the yoke 26 to be forced downwardly to bring the 45 roller 24 nearer the roller 21. A flat wick 28 of suitable absorbent material is passed between the rollers 21 and 24 with its outer terminal dipping in the water within the receptacle 17. The wick 28 passes through 50 the slot 14 and rests upon the plate 15, being supported by said plate within the channel in a pendent position, as seen in Fig. 2.

The water will be absorbed by the wick and raised by capillary attraction from the 55 receptacle 17 between the rollers 21-24 and thence over the plate 15 to the depending

portion of the wick within the cold air channel. Moisture is thus supplied to the air to humidify it. The roller 24 can be rotated for adjusting the wick, and the screw 27 can be adjusted to regulate the pressure upon the wick between the rollers, whereby to regulate the amount of moisture which is permitted to pass between the rollers into the cold air channel. It is thus possible to adjust the 70 wick and to adjust the pressure roller 24, in order that the amount of moisture supplied to the air can be controlled to a nicety.

One side of the channel 7 which has the humidifying means is provided with a glass 75 window 29, through which the lower end of wick 28 can be seen, to note the condition thereof. Said side of the channel is provided below the window 29 with an opening 30 normally closed by a vertically sliding 80 door 31 movable in guides 32 attached to the channel, whereby access may be had into the lower portion of the channel. A tray 33 is 85 slidable through the side of the channel 7 below the door 31 and is normally disposed below the wick 28 to catch the drippings, a felt or other suitable pad 34 being disposed within the tray 33 to absorb the drippings, and to collect the dust from the air. The tray 33 can be drawn out of the channel for 90 cleaning it.

Having thus described the invention, what is claimed as new is:

A furnace embodying a jacket having opposite lower inlet openings, a register box 95 above the upper end of the jacket and having openings in its opposite sides extending to the lower edges thereof, opposite vertical channels having their upper ends attached to said sides of said box around the openings 100 thereof and having their flanges projecting inwardly, said channels and box providing an arch-like structure straddling the jacket with the lower edge of the box seating upon the upper end of the jacket and the edges of 105 the channel flanges secured to opposite sides of said jacket whereby air flowing through said channels comes in contact with the jacket, the lower ends of the channels communicating with said inlet openings of the 110 jacket, a hot air pipe rising from the upper end of the jacket within said box and a register fitted upon said box and the upper end of said pipe.

In testimony that I claim the foregoing 115 as my own, I have hereto affixed my signature in the presence of two witnesses.

JOHN Z. MILLER.
